ATTORNEY

UNITED STATES PATENT OFFICE.

HEINRICH ORTGIES, OF ERFURT, BELGIUM.

SELF-LOADING PISTOL.

1,403,705.

Specification of Letters Patent. Patented Jan. 17, 1922.

Application filed April 1, 1919. Serial No. 286,816.

To all whom it may concern:

Be it known that I, HEINRICH ORTGIES, manufacturer, citizen of the German Republic, residing at No. 30 Cyriakstrasse, in the city of Erfurt, Germany, have invented certain new and useful Improvements in Self-Loading Pistols, (for which I have filed applications in Germany, July 3, 1916, Patent No. 307,635, Austria, May 25, 1917, and Hungary, June 23, 1917,) of which the following is a specification.

The present invention relates to improved means for securing the barrels of automatic pistols, according to which the barrel is provided with a specially-constructed stud for engagement in a hole in the handle. With the known arrangements of this kind it is necessary for securely fixing the barrel, to employ a separate bar, which is inserted into a groove formed partly in the breech and partly in the barrel; this is both tedious and expensive. It is the object of the present invention to obviate this drawback and to ensure an absolutely rigid fit of the barrel. For this purpose the stud on the barrel is provided, according to the present invention, with lateral extensions, which after the stud has been introduced into the hole in the handle, and the barrel has been swung around will engage with corresponding enlargements of the stud hole.

In the drawing a constructional form of this arrangement for securing the barrel is exemplified on an automatic pistol with a breech sliding on the handle and enclosing the barrel.

Fig. 1 is a side view. Fig. 2 is a top view of the pistol with the breech partly broken away. Fig. 3 is a top view of the front part of the handle. Fig. 4 is a side view of the rear part of the barrel and Fig. 5 is a bottom view of the same.

The general arrangement of the pistol shown is of the known kind. At the rear lower end of the barrel is provided a stud *b*, which has two lateral extensions or wings *c*

and *d*. Corresponding to the shape of this stud a hole or recess *f* is provided in the handle *e*; this recess is undercut and has two enlargements through which the extensions *c* and *d* of the stud may enter when the barrel is held at right angles to the axis of the pistol, as shown by dotted lines in Fig. 2. When, therefore, the breech *g* has been removed, the barrel may be readily removed by turning it in the manner described, and it may be refitted in a similar manner; when swung into axial position, it will be then locked to the handle with the known bayonet lock.

In place of the two extensions *c* and *d*, a greater number of such extensions may be provided, in which case, of course, the undercutting of the recess must also be accordingly arranged.

The character of this lock allows of dimensioning the engaging parts in such a manner that they will have a great strength. The correct position of the barrel relative to the handle is ensured by a stop *h*, which engages in a recess *i* provided on one side in the rear end of the barrel. The engaging parts are so made that when the barrel is moved into its normal position, a strong clamping effect is produced, which may however, be easily overcome as the barrel is employed as a lever.

What I claim to secure by Letters Patent of the United States is:—

Improvement for securing the barrel of self-loading pistols consisting of a stud on the breech end of the barrel and at right angles thereto, said stud having lateral extensions, in the handle a recess of corresponding shape and undercut to receive said winged stud when the barrel is held at right angles to its normal position, and to hold said barrel, when swung into normal position.

In testimony whereof I affix my signature.

HEINRICH ORTGIES.
